Primary Examiner — T. Chase Nelson*Assistant Examiner* — Michael A Pratt(74) *Attorney, Agent, or Firm* — Husch Blackwell LLP(57) **CLAIM**

The ornamental design for the accessory rail, as shown and described.

DESCRIPTION

FIG. 1. is a perspective view of a first embodiment of the accessory rail of the subject invention.

FIG. 2 is a top view of the accessory rail of FIG. 1.

FIG. 3. is a side view of the accessory rail of FIG. 1, the opposite side being a mirror image thereof.

FIG. 4. is a bottom view of the accessory rail of FIG. 1.

FIG. 5. is a front view of the accessory rail of FIG. 1, the opposite side being a mirror image thereof.

FIG. 6 is a top view of a second embodiment of the subject invention; and,

FIG. 7 is a bottom view of a second embodiment of the subject invention.

The remaining views of the second embodiment are identical to the first embodiment.

All of the other sides of the second embodiment are the same as the first embodiment except for the width of the 4th channel from the left in FIG. 6 and the broken line boundaries in FIGS. 6 and 7.**1 Claim, 3 Drawing Sheets**FIG. 1

FIG. 2

FIG. 3

FIG. 4

FIG. 5

FIG. 6

FIG. 7
